DESIGN FOR A FLOWER HOLDER OR SIMILAR ARTICLE

Myrtle L. Mullineaux, Mount Airy, Md.

Application July 28, 1944, Serial No. 114,601

Term of patent 7 years

(Cl. D29—28)

To all whom it may concern:

Be it known that I, Myrtle L. Mullineaux, a citizen of the United States, residing at Mount Airy, in the county of Howard and State of Maryland, have invented a new, original, and ornamental Design for a Flower Holder, or Similar Article, of which the following is a specification, reference being had to the accompanying drawing, forming a part thereof.

I claim:

The ornamental design for a flower holder, or similar article, as shown.

MYRTLE L. MULLINEAUX.
